(51) **LOC (13) Cl.** **13-03**

CLAIM

(52) **U.S. Cl.**

The ornamental design for a circuit board for power semiconductor module, as shown and described.

USPC **D13/182**

DESCRIPTION

(58) **Field of Classification Search**

FIG. 1 is a front, top and left side perspective view of a circuit board for power semiconductor module showing our new design;

FIG. 2 is a front view thereof;

FIG. 3 is a top plan view thereof;

FIG. 4 is an enlarged right side view thereof; and,

FIG. 5 is an enlarged left side view thereof.

The even broken lines illustrate portions of the circuit board for power semiconductor module that form no part of the claimed design. The dash-dotted lines denote the boundary of the claim and form no part of the claimed design.
